DOOR CHECK

Wallace F. Moore, New Britain, Conn., assignor to
The American Hardware Corporation, New
Britain, Conn., a corporation of Connecticut

Application April 27, 1933, Serial No. 668,252

9 Claims. (Cl. 16—70)

My invention relates to door checks and closers, and has special reference to such devices for use on screen and other doors of light construction.

5 The principal objects of my invention are to provide a device of this character which is simple, strong and durable in construction, may be easily and quickly installed, may be easily adjusted to vary the door closing action thereof, and is symmetrical in design when two of the devices are used together, one for right-hand and the other for left-hand operation.

10 These and other objects of my invention and features whereby they may be attained, will be readily understood from the following description and accompanying drawings, in which:

15 Figure 1 is a sectional plan view, partly broken away, of a door check embodying the features of my invention in their preferred form, the door check being shown applied to a door and its casing;

Fig. 2 is a side elevation of the check;

Fig. 3 is a detail sectional view taken on the line 3—3 of Fig. 1;

20 Figs. 4 and 5 are sectional views taken on the lines 4—4 and 5—5 of Fig. 3; and

Fig. 6 is a detail sectional view taken on the line 6—6 of Fig. 1.

25 My improved device is illustrated in the drawings as applied to a door 2 and a door-casing 4. As shown, the device is provided with a cylinder 6, and a piston 8 having a rod 10 extending out through one end of the cylinder. This end of the cylinder has a cap 12 screw-threaded thereon and provided with an aperture through which the piston rod slides during the operation of the device. The other or outer end of the cylinder is closed by a cap 14 which is provided with an air vent 16, the flow of air through which being regulated by a thumb-screw 18. The outer end of the device may be connected with a door by means of a lug 20 on the cap 14 which is pivoted on a cotter pin 22 that extends through depending bracket arms or lugs 24 on a bracket 26 that is secured by screws 27 to the door.

30 In accordance with the present invention, novel and improved spring actuated door closing means is provided for connecting the outer end of the piston rod with the door casing. As shown, this means comprises a U-shaped bracket 28 which may be secured by bolts 29 to a bracket plate 30 that is secured by wood screws 31 to the door casing. The outer end portions 35 of the arms of the bracket are provided with

apertures through which extend a post or pin 32, the pin being secured to the bracket arms by means of a head 34 on one end thereof which engages the outer side of one of the arms, and a cap-screw 36 screw-threaded into an aperture in the other end of the bolt and engaging the outer side of the other arm.

35 Dogs 38 in the form of annular disks are mounted on the pin 32 with their outer surfaces, which are flat, respectively engaging the inner sides of the arms. The dogs are held from inward movement by a sleeve 39 that has its ends abutting the inner sides of the dogs. A cylindrical casing 40 has its ends mounted on the dogs 38. One of the dogs 38 is provided with a radial projection 42 which is received in a slot in the adjacent end of the casing 40 so as to lock the casing and dog together. The other dog is provided with an outward projection 44 which is received in a slot in one of the arms 20 of the bracket 28 so as to lock this dog to the bracket. A spring 46 is coiled about the pin 32 and has its end portions surrounding inwardly projecting hubs 48 on the dogs. The ends of the coiled spring are hooked over lugs 50 on the dogs so as to respectively secure them to the dogs. A split clamping ring 52 surrounds the casing 40 and is held in central position axially of the casing by means of outwardly projecting lugs 54 on the casing which engage 30 opposite edges of the ring. The ring is adapted to be clamped in different angular positions to the casing by means of a screw 56. The split ring is connected with the outer end of the piston rod 10 by means of a boss 58 thereon 35 into which the end of the rod is screw-threaded. The clamping ring is provided with a projection forming stop shoulders 57 that are adapted to engage one of the lugs 54 to limit the extent of the adjustment of the ring on 40 the casing.

45 To install the device, the bracket plate 30, is secured to the door case in the desired position. With the check assembled, the U-shaped bracket 28 is attached to the plate 30 by means of the bolts 29, the bolts being inserted through apertures in the outer end of the bracket 28 and the bolt nuts applied. The only difference in the manner of attaching the device to right and left hand doors to cause the door closing 50 spring to operate in the right direction, is that the check is reversed in position with respect to the top and bottom sides of the bracket 28. To determine which side shall be uppermost, each side of the bracket bears an arrow 59, 55

and it is only necessary in applying the check to either right or left hand doors to position it so that the arrow on the top side of the U-shaped bracket points toward the door.

- 5 When the device has thus been applied to the door-case 4, the cylinder 6 is slid outwardly so that about one quarter inch of the piston rod 10 is showing, and then the location for the outer screw-hole of hinge plate or bracket 26 is marked.
- 10 10 The cotter pin 22 may then be removed and the hinge plate attached. The cotter pin is then replaced to complete the attachment of the device to the door and door-case.

To change the tension of the door closing spring, 15 the cotter pin 22 is removed and the clamping ring 52 loosened. The spring casing 40 is held from turning with one hand, and the clamping ring is slipped around the casing, away from the door to increase the tension and toward the door 20 to decrease the tension. When the tension of the spring has been thus adjusted, the clamping ring is secured in position and the cotter pin 22 replaced. The checking action may be adjusted by turning the valve screw 18.

25 During adjustment of the door closing spring, the stop shoulders 57 by engagement with one of the lugs 54 prevents the spring from being overwound, and also prevents turning the clamping ring in the wrong direction from the untensioned 30 position of the spring.

A feature of considerable practical importance in a spring tensioning device of the type illustrated, is the arrangement of the dogs 48 on the post 32 with the sleeve 39 between them. This 35 sleeve ensures that the dog which carries the lug 44 cannot be depressed sufficiently to disengage the lug from the slot in the arm of the bracket 28.

The check may be removed from the door case 40 and door, by detaching it from the bracket plate 30 and the hinge plate 26. The bracket plate and hinge plate may be left on the case and door, so that when the door is again hung, the check may be easily applied. This obviates the necessity of 45 boring new holes for the wood screws each time the door and check are used.

My improved device is of simple, strong and durable construction, may be easily and quickly applied to either right or left hand doors without 50 disassembling of parts, and the door closing spring placed under the desired tension without difficulty. The casing supported between the arms of the U-shaped bracket, and the arrangement of the spring and associated parts therein, 55 provides a strong and compact construction, which is symmetrical in design when two of the devices are used together, one for right-hand and the other for left-hand operation.

60 The present application is in part a continuation of my pending application Serial No. 566,396, filed October 2, 1931.

As will be evident to those skilled in the art, my invention permits various modifications without departing from the spirit thereof or the scope of 65 the appended claims.

What I claim is:

- 70 1. In a door check of the class described, the combination, of a structure comprising a cylinder and a piston within the cylinder having a rod extending out through one end of the cylinder, a U-shaped bracket, a pin connecting the outer end portions of the arms of the bracket, dogs mounted on said pin adjacent the inner sides of 75 said arms, respectively, a coiled spring surround-

ing said pin with its ends respectively secured to said dogs, a cylindrical casing surrounding said spring with its ends supported by said dogs, one of said dogs being secured to one of said bracket arms and the other dog being secured to said 5 casing whereby upon turning the casing in one direction the spring may be tensioned, a ring surrounding said casing and secured to one end of said structure, and means for detachably securing said ring to the casing in different angular 10 positions.

2. In a door check of the class described, the combination, of a structure comprising a cylinder and a piston within the cylinder having a rod extending out through one end of the cylinder, a bracket, a spring mounted on the bracket, a casing surrounding said spring and mounted for turning movement on said bracket, one end of said spring being secured to said casing and its other end being secured to said bracket where- 15 by upon turning the casing in one direction the spring may be tensioned, and means for securing the casing and one end of said structure together 20 having provision for adjustment to vary the angular position of said structure with relation to 25 the casing.

3. In a door check of the class described, the combination, of a structure comprising a cylinder and a piston within the cylinder having a rod extending out through one end of the cylinder, a U-shaped bracket, a spring mounted between the arms of the bracket, a casing surrounding said spring and mounted for turning movement between the arms of the bracket, one 30 end of the spring being secured to said casing and its other end being secured to said bracket where- 35 by upon turning the casing in one direction the spring may be tensioned, and means for securing the casing to one end of said structure 40 having provision for adjustment to vary the angular position of said structure with relation to 45 the casing.

4. In a door check of the class described, the combination of a structure comprising a cylinder and a piston within the cylinder having a rod extending out through one end of the cylinder, a bracket, a spring mounted on the bracket, a cylindrical casing surrounding said spring and mounted for turning movement on said bracket, one end of said spring being secured to said casing and its other end being secured to said bracket, where- 50 by upon turning the casing in one direction the spring may be tensioned, and means for securing the casing to one end of said structure comprising an annular member surround- 55 ing said casing, and means for securing said annular member in different angular positions to the casing.

5. In a door check of the class described, the combination, of a structure comprising a cylinder and a piston within the cylinder having a rod extending out through one end of the cylinder, a bracket, a pin secured to the bracket, dogs mounted on said pin in spaced relation, a coiled spring surrounding said pin with its end portions respectively secured to said dogs, a casing surrounding said spring and supported by said dogs, one of said dogs being secured to said bracket and the other being secured to said casing where- 60 by upon turning the casing in one direction the spring may be tensioned, and means for securing said casing and one end of said structure, having provision for adjustment to adjust the position 65 of said structure circumferentially of the casing. 70 75

6. In a door check of the class described, the combination of a structure comprising a cylinder and a piston within the cylinder having a rod extending out through one end of the cylinder, a bracket, a spring mounted on the bracket, a cylindrical casing surrounding said spring and mounted for turning movement on said bracket, one end of said spring being secured to said casing and its other end being secured to said bracket, whereby upon turning the casing in one direction the spring may be tensioned, and means for securing the casing to one end of said structure comprising a clamping ring embracing the casing adapted to be turned thereon, and means 15 for securing said ring to the casing in different angular positions, said ring and casing having stops for limiting the turning movements of the ring on the casing in both directions.
7. In a door check of the class described, the combination of a structure comprising a cylinder and a piston within the cylinder having a rod extending out through one end of the cylinder, a bracket, a pin secured to the bracket, dogs mounted on said pin in spaced relation, a coiled 20 spring surrounding said pin with its ends respectively secured to said dogs, a casing surrounding said spring and dogs, one of said dogs being secured to said bracket and the other being secured to said casing whereby upon turning the casing in one direction the spring may be tensioned, the dog secured to the bracket having a lug and the bracket having a slot for receiving the lug to secure said dog to the bracket, a sleeve surround-

ing said pin with its ends substantially in abutting engagement with the inner sides of said dogs, and means for securing said casing and one end of said structure together.

8. The combination of a pin, a spring coiled 5 about the pin, dogs mounted on the pin and respectively secured to the ends of said spring whereby upon relatively turning the dogs the spring may be tensioned, a member extending over the outer end face of one of the dogs, said 10 member having a slot extending therethrough and the adjacent dog having a lug extending into the slot, and a sleeve surrounding the pin with its ends substantially in abutting engagement with the inner end faces of said dogs to prevent 15 the dog adjacent the said member from being moved inwardly on said pin.

9. In a door check of the class described, the combination of a structure comprising a cylinder and a piston within the cylinder having a 20 rod extending out through one end of the cylinder, a U-shaped bracket, a pin connecting the outer end portions of the arms of the bracket, dogs mounted to turn on said pin adjacent the inner sides of said bracket arms, one of the dogs 25 being secured to said bracket and the other dog being rotatably fixed with relation to said structure so as to turn therewith, a coiled spring surrounding said pin with its ends respectively secured to the dogs, and means for adjusting the 30 relative angular positions of said dogs to vary the tension of the spring.

WALLACE F. MOORE.
